UNITED STATES PATENT OFFICE.

ANDREW GUNDELFINGER, OF JEFFERSON CITY, MISSOURI.

VEHICLE-SEAT.

SPECIFICATION forming part of Letters Patent No. 241,587, dated May 17, 1881.

Application filed September 27, 1880. (Model.)

To all whom it may concern:

Be it known that I, ANDREW GUNDELFINGER, of Jefferson City, in the county of Cole and State of Missouri, have invented certain new and useful Improvements in Vehicle-Seats; and I do hereby declare that the following is a full, clear, and exact description of the invention, which will enable others skilled in the art to which it appertains to make and use the same, reference being had to the accompanying drawings, which form a part of this specification, and in which—

Figure 1 is a plan view of a wagon box or body fitted with my improved seat. Fig. 1^a is a detail view of the seat-locking mechanism. Fig. 2 is a rear elevation of my sectional swinging seat; and Fig. 3 is a similar view, showing a modification in the arrangement of the swinging seat-sections.

Similar letters of reference indicate corresponding parts in all the figures.

My invention has relation to seats for vehicles; and it consists in an improved construction of a sectional swinging seat, as hereinafter described, and particularly pointed out in the claim.

In the accompanying drawings, A is the box or body of a spring-wagon of any approved construction, upon the bottom of which, midway between its sides and at suitable distances apart, are cleats a' a'.

B is the seat-support, the diverging legs of which are made with flanges fitting into the cleats a', and by making these cleats converging and providing the supports B with a hinged plate, b, having a downward-projecting pin, b', which fits into a socket in the bottom of the wagon-box, the seat-supports may be held firmly yet detachably in their respective places in the wagon-box.

Each of the seats is made in two parts, C C. In Fig. 2 I have shown these sections hinged upon a pintle, f, which is attached to the seat-

support B, the outer end of each seat-section being supported upon the sides of the wagon-box A and held in place by the locking device shown clearly in the detail view, Fig. 1^a. This device is simply a rod hinged in the outer end of the seat-section and bent to form a crank, g', which may be turned down to interlock with ears or catches h h, projecting from the wagon-sides. Other means of fastening the seat-sections may be adopted, if desired.

Instead of hinging the seat-sections together upon the middle support, B, this arrangement may be reversed, as shown in Fig. 3, in which each of the seat-sections is provided with a pintle, c, at its outer end, which fits into sockets arranged on the inner sides of the wagon-box sides. The inner end of each seat-section has a short stud or pin, c', which, when the seat-sections are swung back in their locked or closed position, bears against the front side of the middle support, B, and thus prevents the seats from being swung too far back when occupied.

I prefer to construct the wagon-box with a folding end-gate, D, which, by unfolding its several hinged sections, forms a convenient means of access to the wagon from the rear, and by opening the swinging seat-sections the front part of the wagon may readily be reached.

Having thus described my invention, I claim and desire to secure by Letters Patent of the United States—

The combination of the wagon box or body A, detachable seat-supports B, and detachable swinging seat-sections C C, substantially as and for the purpose herein shown and specified.

In testimony that I claim the foregoing as my own I have hereto affixed my signature in presence of two witnesses.

ANDREW GUNDELFINGER.
